STROKER AND MOUNTING FOR SANDING MACHINES

David S. Oakley, Bristol, Tenn.

Application January 22, 1934, Serial No. 707,822

13 Claims. (Cl. 51—143)

The invention relates to a stroker and mounting for sanding machines and more especially to an attachment of this character for single or double belt sanding machines.

5 The primary object of the invention is the provision of an attachment of this character, wherein a stroker for the belt or belts of sanding machines is so supported that it can be positioned and manipulated to have the sanding belts 10 operate upon the work for the sanding and polishing of the same, the stroker in its entirety being of novel construction and susceptible of varying pressures according to the requirements in the sanding and polishing operation of the machine.

15 Another object of the invention is the provision of an attachment of this character, wherein the stroker is susceptible of positioning with respect to a single or double abrasive belt of a sanding machine, whether the abrasive face or faces thereof be outside or inside of the belt or belts, and such stroker is conveniently manually 20 handled for the successful and accurate sanding and polishing of a piece of material to assure a true contact of the belt or belts with the surface 25 of the material during the sanding or polishing of the same when the machine is operating.

A further object of the invention is the provision of an attachment of this character, wherein the stroker head is yieldably and universally 30 mounted to assure a uniform contact throughout the attaching area of an abrasive belt or belts so that the stroker will be self-adjusting according to the lay of the work or piece of material operated upon and a uniformity of pressure of the 35 abrasive belt or belts will be had upon the work during the travel thereof in the operation of the machine and thus accuracy and a proper finish obtained while the work is being sanded or polished.

40 A still further object of the invention is the provision of an attachment of this character, wherein the stroker can be brought into proper relation to an abrasive belt or belts of a sanding and polishing machine for stroking action thereon, to have the same work upon the material or 45 piece of work for the proper sanding and polishing thereof, the stroker being mounted for convenience and easy handling by the operator of the machine and being readily and quickly located 50 and manipulated by said operator.

A still further object of the invention is the provision of an attachment of this character which is comparatively simple in construction, thoroughly reliable and efficient in its purpose, 55 assuring trueness and accuracy in the sanding

and polishing of work, readily and easily adjusted, and inexpensive to manufacture and install.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:

Figure 1 is a side elevation of a sanding and polishing machine, showing the stroker and mount therefor constructed in accordance with the invention.

Figure 2 is a fragmentary sectional view on the line 2—2 of Figure 1, looking in the direction of the arrows.

Figure 3 is a fragmentary sectional view on the line 3—3 of Figure 1, looking in the direction of the arrows.

Figure 4 is a fragmentary top plan view of the stroker mount, the set screw for the guide track being in section to disclose in detail the extent of shift of such track.

Figure 5 is a fragmentary sectional view on the line 5—5 of Figure 4, looking in the direction of the arrows.

Figure 6 is a fragmentary sectional view on the line 6—6 of Figure 4, looking in the direction of the arrows.

Figure 7 is a sectional view on the line 7—7 of Figure 4, looking in the direction of the arrows.

Figure 8 is an enlarged vertical transverse sectional view through the stroker, taken on the line 8—8 of Figure 9 looking in the direction of the arrows.

Figure 9 is a sectional view on the line 9—9 of Figure 8, looking in the direction of the arrows.

Figure 10 is a sectional view on the line 10—10 of Figure 9, looking in the direction of the arrows.

Figure 11 is a sectional view on the line 11—11 of Figure 9, looking in the direction of the arrows.

Figure 12 is a sectional view on the line 12—12 of Figure 11, looking in the direction of the arrows.

Figure 13 is a sectional view on the line 13—13 of Figure 8, looking in the direction of the arrows.

Figure 14 is a sectional view on the line 14—14 of Figure 8, looking in the direction of the arrows.

Figure 15 is a sectional view on the line 15—15 of Figure 8, looking in the direction of the arrows.

Figure 16 is an enlarged detail plan view of the base frame of the carriage.

Figure 17 is a top plan view of the side plate of the carriage.

Figure 18 is a side elevation of a slight modification of stroker and mount.

5 Figure 19 is a fragmentary side elevation of the structure shown in Figure 18 except that the stroker has been differently located with respect to the sanding belt of the sanding and polishing machine, the belt in Figure 18 being an inside 10 sander and that in Figure 19 an outside sander.

Similar reference characters indicate corresponding parts throughout the several views in the drawings.

Referring to the drawings in detail, except 15 Figures 18 and 19 there is generally shown a sanding and polishing machine comprising end stands A and B and an intermediate work supporting stand C, respectively, and such end stands carry the pulleys 10 and 11 for traveling 20 sanding and polishing belts 12, there being preferably two arranged in spaced edge to edge relation to each other, one being a rough sanding belt and the other a fine sanding or polishing belt. The pulleys 10 are the power pulleys and 25 each is driven from an electric motor 13, while the pulleys 11 are the guide pulleys for said belts, and the detailed construction of said sanding and polishing machine is the subject matter of an application for patent filed on or about the 22nd 30 day of January, 1934 and bearing the title Sanding machine and Serial No. 707,821, which machine constitutes no part of the present invention hereinafter fully described.

The attachment constituting the present invention comprises a pair of standards 14 and 15, respectively, the latter being a straight one while the standard 14 is of curvilinear contour this being required of the latter due to the fact that the same is secured to the end stand B, while the standard 15 is secured to the end stand A. Each standard 14 and 15 has formed at its upper end an elongated guide head 16 provided with an undercut channel or groove 17 therein, this terminating a distance removed from both 40 ends of said head. Superimposed upon these heads 16 of the standards 14 and 15 is a double rail track including the spaced parallel side rails 18 and 19, respectively, the spacer pieces 20 and end blocks 21, respectively, the rails being bolted or otherwise made fast to the pieces and blocks, as at 22, to effect the rigid unitary track. Each 45 end block 21 has centrally formed therein an elongated slot 23 for accommodating a set screw 24 threaded into a sliding wedge 25 fitting the undercut groove or channel 17 in the head 16. It should be apparent that the track as a unit can be longitudinally displaced and laterally shifted with respect to the sanding machine upon the heads 16 of the standards 14 and 15. The 50 set screw 24, when tightened, locks the track in its moved or shifted position and thus assuring alignment of such track with respect to the belt or belts 12 of the sanding machine. Each head 15 16 has thereon an upstanding bearing 26 carrying an adjustable abutment screw 27 for the track to regulate and determine the movement in one direction of such track laterally with respect to the machine. The fact that the channel or groove 17 is removed from one end of each head 16 permits the sliding wedge 25 to be extracted or removed from this groove or channel so that such track can be readily released from the standards 14 and 15 when the occasion 60 requires. The screws 27, when adjusted, will prevent the accidental removal of the sliding 70 75

wedges 25 from the groove 17 in the head 16 on the shifting of the track in the direction of such screws 27.

The track, when carried by the standards 14 and 15, will be superposed with relation to the 5 belts 12 of the sanding machine and to some extent will overhang such belts. However, the track in the mounting thereof on the heads of the standards can be shifted on these heads so as to be moved out of the way of an operator 10 when using a hand stroker upon the belts 12 for the sanding and polishing of a piece of work by such belts during the operation of the machine.

Movable upon the track is a carriage which 15 comprises a body section 28 having the seats 29 and 30, respectively, for upstanding bearings 31 and 32, these supporting upper traction rollers 33 which have straight traction peripheries and are movable upon the upper edges of the rails 18 and 19 of the track, while formed with the body 20 section, at the underside thereof, are bearings 34 for the lower rollers 35 and 36, respectively, the 25 rollers 35 being peripherally grooved, as at 37, to receive the tapered tread 38 at the lower edge of the rail 18 of the track, while the roller 36 is alike to the rollers 33 and designed to travel on the lower edge of the rail 19 of said track. By the construction of the rollers 35 the carriage 30 will be interlocked with the track and thus be prevented from running off of the same.

The carriage equipped with the rollers 33, 35 and 36 carries spring pressed wipers 38' for the 35 rails 18 and 19 of the track to keep the same clean during the operation of the sanding and polishing machine and manipulation of the stroker.

The body section 28 is formed with a projected 40 frame 39 and fixed to the underside of the said body section, to be disposed transversely of the carriage are the spaced guide rails 40 for a shiftable slide 41, this carrying a resilient bumper 42 alternately engageable with stops 43 integral with the said body section at the under face thereof, so that the slide will be limited in its movement to the extent between the said stops 43. The 45 slide 41 is formed with a central boss 44 in which is slidably fitted a stem or post 45, the same being also slidably fitted in a brace arm 46 unitary with the body section 28. This stem or post 45, at its lower end, has the ball and socket connection 47 with a stroker head 48, the ball and socket connection 47 being centrally thereof. About the lower portion of the stem or post 45 is fixedly arranged a spider 49 and through the 50 same work the pins 50 joined with and upstanding from the head 48. These pins have about the same coiled tensioning springs 51 which work against the spider 49 and against tensioning nuts 52 upon said pins 50. Thus it will be seen that the head 48 is tensioned and is self-adjusting for 55 uniformity of contact with a part.

Detachably clamped over the working side of the head 48 is a covering 53 enveloping a cushion or pad 54 which is inwardly of the covering 53 and against the said head, the covering 53 being 60 removably clamped to the head by the fasteners 55.

About the stem or post 45, between the brace 65 46 and the boss 44, is a collar 56, the same being fixed to said stem or post by a pin 57, and hinged to this collar 56 by a pivot 58 is the fork 59 for a handle or manually operable lever 60. The arms 61 of said fork are connected by a pivot 62 to a link 63 which, by the pivot 64, is swingingly connected to the brace 46 for suspension beneath the body section 28 of the carriage.

Forwardly of the stem or post 45 and fixed in the slide 41 is a depending guide bolt 65, the same being slidable through an eye 66 on the collar 56 and supporting a coiled expansion spring 67 at its lower end, which spring is seated upon an adjusting nut 68 on the belt and plays against the eye 66 so as to hold the head 48 normally neutral or in raised position out of contact with either belt 12 of the sanding and polishing machine.

10 It should be apparent that by manually moving the handle 60 the stroker can be shifted longitudinally on the track rails 18 and 19 or the slide 41 moved laterally or transversely of the carriage, as well as depressing the head 48, which latter, by the universal connection, is flexible for a firm contact with either belt 12 in the operation of the sanding and polishing machine.

The rail 18 of the track has mounted thereon, 20 near opposite ends of said track, the bumpers 69 to limit the throw of the carriage on the track and also to cushion such carriage at the limits of its strokes.

25 The carriage is equipped with electric light bulbs 70 which depend therefrom and are serviceable to a user of the machine.

In Figures 18 and 19 of the drawings there is shown a slight modification of stroker equipment, wherein the track 71 for the carriage 72 is supported upon pedestals 73 and such track is susceptible of being shifted laterally on these pedestals so that said track can be properly located with respect to the sanding and polishing machine belt 74 and which machine, in this instance, 35 is of the single belt type. The carriage 72 has the stroker head 75 stationarily mounted thereon. When it is desired to operate a hand stroker the track 71 is moved laterally to one side of the machine so as to be out of the way and have the head 75 not interfere with the hand stroking action of the belt 74. The pedestals 73 for the track 71 are readily portable and can be located in a position optional with the user of the attachment.

40 In Figure 19 of the drawings the stroker head 75 is located to operate against the inner face of the belt 74 as, in this instance, the abrasive is at the outside of the belt, whereas in Figure 18 the abrasive is at the inside of the belt, it being apparent that the pedestals 73 can be of the desired height to locate the head 75 foremost with relation to the belt 74 or between the upper and lower stretches thereof as does appear in said Figures 45 18 and 19.

45 From the foregoing it is thought that the construction and manner of operation of the stroker attachment for the sanding and polishing machine will be clearly apparent and, therefore, a more extended explanation has been omitted. However, it is to be understood that changes, variations and modifications may be made in the structure as fall properly within the scope of the appended claims without departing from the spirit of the invention or sacrificing any of its advantages.

50 What is claimed is:

1. The combination of a pair of uprights adapted for location with respect to a sanding and polishing machine having a traveling belt, a track supported upon said uprights for longitudinal and lateral adjustment, a carriage movable upon the track, a stroking head supported by the carriage for vertical movement, and a handle operatively connected with said head for lowering thereof into contact with the belt.
2. The combination of a pair of uprights adapted for location with respect to a sanding and polishing machine having a traveling belt, a track supported upon said uprights for longitudinal and lateral adjustment, a carriage movable upon the track, a stroking head supported by the carriage for vertical movement, a handle operatively connected with said head for lowering thereof into contact with the belt, and means yieldably supporting said head.
3. The combination of a pair of uprights adapted for location with respect to a sanding and polishing machine having a traveling belt, a track supported upon said uprights for longitudinal and lateral adjustment, a carriage movable upon the track, a stroking head supported by the carriage for vertical movement, a handle operatively connected with said head for lowering thereof into contact with the belt, means yieldably supporting said head, and a universal connection between the head and its supporting means.
4. The combination of a pair of uprights adapted for location with respect to a sanding and polishing machine having a traveling belt, a track supported upon said uprights for longitudinal and lateral adjustment, a carriage movable upon the track, a stroking head supported by the carriage for vertical movement, a handle operatively connected with said head for lowering thereof into contact with the belt, means yieldably supporting said head, and a universal connection between the head and its supporting means, and a slide fitted in the carriage and carrying the head supporting means.
5. The combination of a pair of uprights adapted for location with respect to a sanding and polishing machine having a traveling belt, a track supported upon said uprights for longitudinal and lateral adjustment, a carriage movable upon the track, a stroking head supported by the carriage for vertical movement, a handle operatively connected with said head for lowering thereof into contact with the belt, means yieldably supporting said head, a universal connection between the head and its supporting means, a slide fitted in the carriage and carrying the head supporting means, a pair of rails included with said track, one of said rails having a beveled tread, and traction rollers carried by said carriage and engageable with the rails, certain of the traction rollers being peripherally grooved for interfitting with the beveled tread of one rail.
6. The combination of a pair of uprights adapted for location with respect to a sanding and polishing machine having a traveling belt, a track supported upon said uprights for longitudinal and lateral adjustment, a carriage movable upon the track, a stroking head supported by the carriage for vertical movement, a handle operatively connected with said head for lowering thereof into contact with the belt, means yieldably supporting said head, a universal connection between the head and its supporting means, a slide fitted in the carriage and carrying the head supporting means, a pair of rails included with said track, one of said rails having a beveled tread, traction rollers carried by said carriage and engageable with the rails, certain of the traction rollers being peripherally grooved for interfitting with the beveled tread of one rail, stops on said carriage, and a resilient bumper on the slide for abutment with said stops.
7. The combination of a pair of spaced stands, uprights fixed to said stands and having a material lateral spread, a pair of traveling abrasive

belts mounted upon the stands for lateral displacement with respect to the uprights and disposed edge to edge, a double rail track supported for sidewise movement on the uprights, a carriage movable on the track and having rollers traversing the double rails, and a stroker head on the carriage and movable to operative and inoperative positions with relation to the respective belts.

8. The combination of a pair of spaced stands, uprights fixed to said stands and having a material lateral spread, a pair of traveling abrasive belts mounted upon the stands for lateral displacement with respect to the uprights and disposed edge to edge, a double rail track supported for sidewise movement on the uprights, a carriage movable on the track and having rollers traversing the double rails, a stroker head on the carriage and movable to operative and inoperative positions with relation to the respective belts, and means for moving the double rail track in the sidewise direction.

9. The combination of a pair of spaced stands, uprights fixed to said stands and having a material lateral spread, a pair of traveling abrasive belts mounted upon the stands for lateral displacement with respect to the uprights and disposed edge to edge, a double rail track supported for sidewise movement on the uprights, a carriage movable on the track and having rollers traversing the double rails, a stroker head on the carriage and movable to operative and inoperative positions with relation to the respective belts, means for moving the double rail track in the sidewise direction, and means for securing the said track in its adjusted position.

10. The combination of a pair of spaced stands, uprights fixed to said stands and having a material lateral spread, a pair of traveling abrasive belts mounted upon the stands for lateral displacement with respect to the uprights and disposed edge to edge, a double rail track supported for sidewise movement on the uprights, a carriage movable on the track and having rollers traversing the double rails, a stroker head on the carriage and movable to operative and inoperative positions with relation to the respective belts, means for moving the double rail track in the sidewise direction, means for securing the said track in its adjusted position, and a source of power on one of the stands and operating said belts.

11. The combination of a pair of spaced stands, uprights fixed to said stands and having a material lateral spread, a pair of traveling abrasive belts mounted upon the stands for lateral dis-

placement with respect to the uprights and disposed edge to edge, a double rail track supported for sidewise movement on the uprights, a carriage movable on the track and having rollers traversing the double rails, a stroker head on the carriage and movable to operative and inoperative positions with relation to the respective belts, means for moving the double rail track in the sidewise direction, means for securing the said track in its adjusted position, a source of power on one of the stands and operating said belts, and means for mounting the head for universal movement and yieldability.

12. The combination of a pair of spaced stands, uprights fixed to said stands and having a material lateral spread, a pair of traveling abrasive belts mounted upon the stands for lateral displacement with respect to the uprights and disposed edge to edge, a double rail track supported for sidewise movement on the uprights, a carriage movable on the track and having rollers traversing the double rails, a stroker head on the carriage and movable to operative and inoperative positions with relation to the respective belts, means for moving the double rail track in the sidewise direction, means for securing the said track in its adjusted position, a source of power on one of the stands and operating said belts, and means for mounting the head for universal movement and yieldability, and manually operated means for bringing the head into active position with relation to said belts.

13. The combination of a pair of spaced stands, uprights fixed to said stands and having a material lateral spread, a pair of traveling abrasive belts mounted upon the stands for lateral displacement with respect to the uprights and disposed edge to edge, a double rail track supported for sidewise movement on the uprights, a carriage movable on the track and having rollers traversing the double rails, a stroker head on the carriage and movable to operative and inoperative positions with relation to the respective belts, means for moving the double rail track in the sidewise direction, means for securing the said track in its adjusted position, a source of power on one of the stands and operating said belts, means for mounting the head for universal movement and yieldability, manually operated means for bringing the head into active position with relation to said belts, and spring pressed wipers on the carriage and engaging parts of the rails of the track for the cleaning of said rails.

DAVID S. OAKLEY. 55
